UNITED STATES PATENT OFFICE.

CARL F. ANDERSON, OF CHICAGO, ILLINOIS.

FOLDING AND WRAPPING MACHINE.

1,202,955.

Specification of Letters Patent. Patented Oct. 31, 1916.

Application filed February 15, 1913. Serial No. 748,504.

To all whom it may concern:

Be it known that I, CARL F. ANDERSON, a citizen of the United States, residing at Chicago, in the county of Cook and State of Illinois, have invented certain new and useful Improvements in Folding and Wrapping Machines, of which the following is a specification.

This invention relates to machines for folding magazines, newspapers, or the like, placing a wrapper about each magazine or paper, and pasting together the ends of the wrapper. In prior machines of this character, when for any reason a wrapper was not placed in position to be folded about the magazine, the paste was deposited directly on the magazine. By reason of this failure of the operator or machine to supply the wrapper, the corresponding magazine was spoiled through the mis-application of the paste, and the properly wrapped magazines among which the unwrapped magazine was deposited were smeared with paste, as was also that portion of the mechanism that came into contact with the unwrapped magazine.

One of the objects of this invention is to remedy the evil above referred to.

Another object is to provide improved means for applying the paste.

A further object is to improve the wrapper-folding means.

Another object is to provide means governed by the magazine for controlling the feed of the wrappers.

In the accompanying drawings, Figure 1 is a longitudinal section through a machine embodying the features of my invention. Fig. 2 is a fragmental sectional view taken in a plane at right angles to the plane of Fig. 1. Fig. 3 is a fragmental top plan view of the detector mechanism. Fig. 4 is a fragmental elevation of the side opposite to that shown in Fig. 1. Fig. 5 is a perspective view of a wrapped magazine. Fig. 6 is a detail view showing the means for controlling the feed of the wrappers.

The framework of the machine may be of any suitable construction. Herein it is shown as comprising the end frame members 1 and 2 rigidly secured together. In this framework are supported tapes for feeding a wrapper *a* to a predetermined

point in the machine; rollers and tapes for folding a magazine *b* and depositing the folded magazine on the wrapper; other rollers for folding the wrapper about the folded magazine; means for applying paste to a portion of the wrapper before the wrapper-folding operation is completed; and means for conveying the wrapped magazine to a suitable receptacle.

The wrapper conveying means may be of any ordinary construction. Herein it is shown as consisting of three endless continuously driven tapes 3 extending transversely through the machine and running at one end over a roller 3^a and at its outer end over a stationary feed roller 3^b, the latter roller being mounted in a bracket upon the frame member 2. A feed table 4 is arranged adjacent to the feed roller 3^b. The upper run of the tapes 3 is supported upon a horizontal stationary table 5. Above the tapes is located suitable guide means 6 which may be of the ordinary or any preferred character.

7 is a stop for limiting the movement of the wrapper.

To control the feed of the wrappers, I provide the following described means. An arm 3^c (Fig. 2) is fixed upon a rock shaft 3^d which is mounted in suitable bearings in the machine frame. The arm 3^c carries at its lower end a roller adapted to contact a rotary cam 3^e. A pair of arms 3^f also fixed on the shaft 3^d (only one of the arms being shown in the drawings) carry at their outer ends a feed roller 3^g. The operator moves the sheets of paper along the table 4 onto the feed roller 3^b and the forward end of the conveyor 3, and the cam 3^e in its rotation causes the periodic descent of the feed roller 3^g into contact with the paper lying on the stationary roller 3^b to cause the sheet of paper to be fully moved onto the conveyor 3 which thereafter carries it into the machine. I have provided means for controlling the swinging movement of the arm 3^c to govern the feed of the wrappers. This means will be described later. The magazines *b* are fed, one by one, by the operator from a table 8 onto a suitable conveyor 9 consisting, in this instance, of endless continuously-driven tapes, only one tape being shown in the drawing.

10 is guide means located above the con-

veyer 9, and 11 are guides into the space between which the magazine is moved by the conveyer.

12 is a stop for arresting the travel of the magazine. When so arrested, the magazine lies above a pair of folding rollers 13 and 14, the central portion of the magazine being, in this instance, directly above said rollers. A folding blade 15 carried by arms 16 mounted upon a shaft 17 (all of which may be of the ordinary construction) pushes the middle portion of the magazine downwardly until it is caught by the folding rollers 13 and 14, whereupon said rollers draw the magazine downwardly between them, thereby folding the magazine. As shown in Fig. 1, the conveyer tapes 9 run between the rollers 13 and 14 and thence about a folding roller 18. After the magazine has passed between the folding rollers 13 and 14, the conveyer carries the folded magazine to the folding roller 18 and its coöperating roller 19, the folded edge of the magazine impinging against a stop 20.

21 are guides to prevent displacement of the magazine.

Directly below the pair of folding rollers 18 and 19 is a pair of presser rollers 22. The rollers 18 and 19 are spaced a slight distance apart in order to facilitate the entrance of the folded magazine into the space between said rollers.

23 is a folding blade similar to the blade 15. These blades are swung in unison by means of a cam 23^a (Fig. 4) fixed on the shaft 23^b and acting upon a roller carried by an arm 23^d which is fixed on the shaft 17. The arms that support the folding blades 15 and 23 are connected for synchronous movement through the medium of crank arms 23^e and a link 23^f. A compression spring 23^g holds the roller on the arm 23^d against the cam 23^a. The folding blade 23 bends the magazine downward sufficiently to enable the rollers 18 and 19 to engage it, whereupon said rollers draw the magazine downwardly through the space between them, thereby imparting the second and final fold to the magazine. Upon passing through the space between the rollers 18 and 19, the magazine passes between the pressing rollers 22, whereon the magazine is subjected to considerable pressure in order to flatten the folds.

The table 5 and the stop 7 are so arranged that the positioned wrapper is below and adjacent to the pressing rollers 22. In this instance, the wrapper is intended to be wrapped about the magazine and the ends of the wrapper pasted and lapped. Two folds are therefore given to the wrapper, the folded wrapper being formed of three portions, *c*, *d* and *e*, (Fig. 5) of approximately equal width.

In the table 5 is a slot 24 of sufficient size 65 to allow a magazine and wrapper to pass

downwardly therethrough. Said slot is directly below the adjacent portions of the peripheries of the presser rollers 22. As the folded magazine is fed downwardly by the presser rollers 22, the magazine strikes the wrapper lying upon the table 5 and pushes said wrapper before it as it continues moving downwardly. The magazine and wrapper, as they pass through the slot 24, are caught by rollers 25 and 26, the downward movement of the magazine being arrested by means herein shown as comprising three arms 27 having stop lugs 28 thereon. These arms are fixed upon a shaft 29 which is rigidly mounted in the free ends of two arms 30. The arms 30 are fixed upon a rock shaft 31 journaled in the frame members 1 and 2. Guides 25^a similar to the guides 11 and 21 serve to prevent displacement of the magazine and wrapper.

85

32 is a folding blade of any suitable character arranged to press the wrapper and the adjacent edge of the folded magazine far enough toward the roller 26 and a coöperating folding roller 33 to enable said rollers 90 to engage the wrapper and magazine and complete the folding of the wrapper. Said blade is carried by arms 32^a fixed on a shaft 32^b, said shaft having an arm 32^c bearing a roller which is acted upon by a cam 32^d fixed on a shaft 34. A compression spring 34^a maintains the roller in contact with the cam 32^d. In order to assist in starting the magazine and wrapper properly through the space between the rollers 26 and 33, I impart a slight 100 upward movement to the arms 27 in order thereby to lift the magazine as the folding blade directs it toward said rollers. In order to impart such upward movement to the arms 27 I have mounted them upon the 105 arms 30 as described, and have provided a constantly rotating cam 35 underlying a roller 36 carried by one of the arms 30. A compression spring 36^a holds the roller 36 against the cam 35. As the cam revolves, 110 the arms 30 will be alternately raised and lowered. The cam 35 is fixed upon the shaft 34.

In order further to assist in starting the magazine and wrapper between the rollers 26 and 33, I provide means for separating 115 said rollers slightly. The roller 33 is journaled in arms 37 and 38 fixed upon a rock shaft 39 supported in the frame members 1 and 2. This shaft is turned to lower the roller 33 by means of a cam 40 fixed on the 120 constantly driven shaft 23^b, said cam acting upon a roller 42 carried by the arm 37. A compression spring 42^a maintains the roller 42 in contact with the cam 40.

Before the final fold is imparted to the 125 wrapper, a suitable quantity of adhesive material is deposited upon the wrapper at the proper point to cause the overlapping portions *c* and *e* of the wrapper to adhere to one another. The adhesive-supplying means 130

herein shown comprises a fountain 43 in which two rollers 44 and 45 revolve. A plate 46 having a suitable number of fingers 47 thereon is attached to an arm 48 which is fixed upon a rock shaft 49. The shaft 49 is arranged to be oscillated by means of a cam 50 acting upon a roller 51 carried by an arm 52 which is rigid with the shaft 49. A compression spring 51^a holds the roller 51 in contact with the cam 50. Said cam is of such form as to cause the fingers 47 to be advanced into contact with the periphery of the paste-carrying roller, then withdrawn out of the way of the descending magazine, and then advanced to place their coated end in contact with the portion *c* of the wrapper. In Fig. 5, *f* indicates the dabs of paste deposited on the wrapper by the fingers 47. In the succeeding operation of imparting the final fold to the wrapper, the portion *e* of the wrapper is pressed against the pasted side of the portion *c* of the wrapper, whereby said wrapper portions are caused to adhere to each other. The wrapped magazine, when it emerges from between the rollers 26 and 33, is received between two conveyers 53 and 53^a and is deposited in a receiving trough or packer box 54 of ordinary construction. The upper conveyer 53^a is run at a lower speed than the lower one, so that it exerts a rubbing action upon the overlapping flap of the wrapper to cause the wrapper to be drawn snugly about the magazine.

I have provided means for preventing the application of paste to a magazine for which no wrapper has been supplied. This result is accomplished in the present instance by rendering inoperative the paste-applying device whenever a magazine is presented about which no wrapper has been placed. The arm 52 which moves the arm 48 and paste-applying fingers 47 is extended beyond the roller 51 and has an angular projection 52^a upon its free end. A vertical lever 55 is pivoted between its ends at 55^a in the framework. A coiled compression spring 56 surrounding a rod 57 which is attached to the upper portion of said lever tends to swing the lever to carry its lower end in position to obstruct the upward movement of the projection 52^a on the arm 52, and thus hold the paste-applying fingers 47 in inoperative position. A roller 58 carried upon the upper portion of the lever 55 is engaged by a cam 59 fixed upon the shaft 23^b so that the lever 55 is given an oscillatory movement.

Means is provided for normally holding the lever 55 out of the path of the projection 52^a on the arm 52, and for preventing the roller 58 from following the contour of the cam 59. This means comprises a detector 64 pivoted at 65 to a bracket 66 fixed to a stationary supporting rod 67. The lower portion of said detector is curved and lies in position to be lifted by a wrapper which is

being positioned upon the table 5. Said detector has an upwardly-extending finger 68 which normally underlies one arm 69 of a vertically disposed bell crank also mounted upon the bracket 66. The other arm 70 of said bell crank is connected by a link 71 to one arm of a horizontal bell crank 72 mounted on a bracket 73 fixed in the framework. The other arm of the last mentioned bell crank is connected through the medium of a link 74 to the upper end of the lever 55. When a wrapper underlies the detector 64, the end of the finger 68 lies beneath the arm 69 and prevents the spring 56 from rocking the lever 55 far enough to engage the lug 52^a on the lever 52. If no wrapper is supplied at the proper time, the detector 64 swings downwardly from beneath the bell crank arm 69, thereby allowing the spring 56 to rock the lever 55 and place its lower end in the path of the lug 52^a so that the paste-applying fingers will not contact the magazine for which no wrapper has been provided. It will be understood from Fig. 2 that the detector 64 normally lies upon a wrapper, and that the wrapper lies upon the tapes 3, the latter in turn being supported upon the table 5. When no wrapper is present, the detector swings downwardly through the space between the tapes and into contact with the table 5, such downward movement being sufficient to withdraw the upper end of the finger 68 from below the bell crank arm 69 and prevent operation of the pasting mechanism.

In order to control the feed of the wrappers in accordance with the magazines supplied to the machine, I provide a horizontal rock shaft 77 upon one end of which is fixed a finger 78 having a weighted end 79. The weight of this finger normally tends to raise one end thereof between the tapes 9, and into the path of the magazine just after it passes between the folding rollers 13 and 14. On the other end of the rock shaft 77 is fixed a depending arm 80 having a notched end adapted to engage a laterally projecting lug 81 on the arm 3^c which controls the wrapper-feeding roller 3^c (see Figs. 2 and 6). When the arm 80 is in engagement with the lug 81, the roller on the lower end of the arm 3^c does not follow the contour of the cam 3^c, and the movable feed roller 3^c remains stationary in its lifted position. Whenever a magazine contacts the upwardly extending end of the finger 78 the finger is depressed, the rock shaft 77 is rotated, and the arm 80 is withdrawn from the lug 81 to permit the feed rollers 3^c to descend and move a wrapper onto the conveyer 3. Thus it will be seen that when no magazines are being fed to the machine, no wrappers will be supplied to the conveyer 3.

A bracket 84 is mounted at one end upon a cross bar 85 on the framework, and this

100

105

110

115

120

125

130

bracket carries at its other end a register or counting device 86. This register is operated by an arm 87 thereon which overlies and bears against the upper edge of the first 5 folding knife 15. A spring comprised in the register normally presses the operating arm downwardly and said arm is moved upwardly to actuate the register by the folding knife 15. A feeler finger 88 is pivoted between its ends to a downwardly projecting lug on the bracket 84, the lower end of said feeler finger being arranged to lie in the path of a magazine presented by the conveyer 9. The upper end of the feeler finger 10 is notched or shouldered to engage a projecting pin 89 on the register-actuating arm 87. So long as magazines are continuously fed to the machine, so that a magazine will always underlie the lower end of the feeler finger, the upper end thereof will be held in 15 inoperative position, as indicated in Fig. 1. The actuating arm 87 will therefore follow the movements of the folding knife 15. When, however, no magazine is present beneath the feeler finger 88, the lower end of 20 said finger will swing downwardly, and thus carry the upper notched end into engagement with the pin 89 and prevent the actuation of the register until another magazine is presented. With the parts in this position, each time the folding knife rises it engages the actuating arm 87 and raises it slightly out of contact with the feeler finger, so that should a magazine be presented by 25 the conveyer 9, the finger can be easily swung by the magazine, since the friction between the finger and the stop pin 89 has been removed by the raising of the actuating arm. Until a magazine is presented, the 30 feeler finger occupies the obstructing position, the actuating arm 87 being raised slightly each time the folding knife 15 reaches the upper end of its movement. As will be seen, when magazines are being regularly fed, each time the folding knife descends a magazine will be folded and the 35 register will be actuated, so that an accurate account of the magazines passing through the machine will be recorded. Whether or not there is a magazine present beneath the folding knife, said knife descends regularly, but in this case the feeler finger prevents the actuation of the register. 40

The operation of the machine will, it is thought, be clear from the foregoing description. Illustration of the means for driving the various shafts has been omitted from the drawings, as the invention does not relate thereto and any common or suitable driving means may be employed. 45

The invention is not limited to the precise construction herein disclosed, for various changes may be made in said construction by those skilled in the art without departing from the spirit of the invention. 50

For the sake of brevity, the term "magazine" is used in the claims to denote magazines, catalogues, newspapers and analogous articles.

I claim as my invention:

1. In a machine for wrapping magazines, the combination of means for feeding wrappers into position to receive the magazines, mechanism arranged to fold the magazines and associate them with the wrappers and then to partially fold the wrappers about the magazines and present the magazines into position to have paste applied to the portion of the wrappers inclosing the magazines, means for applying paste to the partially folded wrappers, means for then folding the final flaps of the wrappers about the magazines, and means arranged to prevent the application of paste directly to a magazine in case it should be presented without a wrapper thereon. 70
2. In a machine for wrapping magazines, the combination of magazine-feeding means; wrapper-feeding means; means for folding a wrapper about a magazine; means for applying paste to the wrapper while partially folded about a magazine; and means controlled by a wrapper before its association with a magazine for preventing the application of paste to a magazine about 80 which no wrapper has been placed. 90
3. In a machine for wrapping magazines, the combination of a slotted table, means for successively placing wrappers on said table, means for folding magazines and for pushing a magazine and a wrapper through the slot in said table to partially fold the wrapper about the magazine, means for applying paste to the partially folded wrapper, means for rendering the paste-applying means inoperative when a magazine is presented without a wrapper, and means for completing the fold in the pasted wrapper. 100
4. In a machine for wrapping magazines, the combination of means for feeding wrappers to an assembling point, mechanism arranged to fold magazines and present them to said assembling point and then to partially fold the wrappers about the magazines and present the partially wrapped magazines at a place to receive paste, means for applying paste to a portion of a folded wrapper surrounding a magazine, means for thereafter folding the final flap of the wrapper, and means for detecting the absence of a wrapper at said assembling point and for rendering said paste-applying means inoperative in case a magazine is presented thereto without a surrounding wrapper. 110
5. In a machine for wrapping magazines, the combination of a horizontal slotted table, mechanism for assembling magazines and wrappers at said table and for pushing them through the slot in said table to fold the wrappers about the magazines, means for 120
6. In a machine for wrapping magazines, the combination of a horizontal slotted table, mechanism for assembling magazines and wrappers at said table and for pushing them through the slot in said table to fold the wrappers about the magazines, means for 130

applying paste to the wrappers after passing through said slot, and means governed by the absence of a wrapper on said table for rendering said paste-applying means 5 inoperative.

6. In a machine for wrapping magazines, the combination of a horizontal table, means for placing wrappers on said table, means above said table for folding magazines and 10 placing them in association with the wrappers on said table, means beneath said table to receive the associated magazines and wrappers and complete the folding of the wrappers, means to apply paste to the wrappers before finally folded, and means governed by the absence of a wrapper on said 15 table for rendering said paste applying means inoperative.

7. In a machine for wrapping magazines, 20 the combination of a wrapper feed table, a pair of feed rolls adjacent to the edge of said table, means for periodically raising the upper feed roll out of contact with the lower, magazine feeding means, and means 25 operating in the absence of a magazine in said feeding means to lock said upper feed roll in its raised position.

8. In a machine for wrapping magazines, the combination of means for folding a 30 magazine, means for feeding wrappers into position beneath said folding means so as to receive the folded magazine, wrapper-folding means beneath said wrapper-feeding means arranged to receive the magazine 35 and wrapper and partially fold the wrapper about the magazine, means beneath said wrapper-folding means adapted to apply paste to a portion of the wrapper surrounding the magazine, means for thereafter folding 40 the final flap of the wrapper, and means for preventing the application of paste to a magazine which is presented without any surrounding wrapper.

9. In a machine for wrapping magazines, 45 the combination of means for folding a magazine, means for feeding a wrapper into position to receive the folded magazine, means to receive the wrapper and magazine and partially fold the wrapper about the 50 magazine, means for applying paste to the partially folded wrapper, means for folding the final flap of the wrapper, and two endless belt conveyers located at one end in position to receive the folded and wrapped 55 magazine from the latter folding means, said conveyers being adapted to carry the wrapped magazine to a receptacle, and one of the conveyers running at a greater speed than the other whereby a rubbing action 60 will be exerted upon the wrapper.

10. In a machine for wrapping magazines, wrapper-folding means, means to support a magazine adjacent to said wrapper-folding means, paste-supplying means, an 65 oscillatory paste-applying member arranged

to swing across the path of the magazine into contact with the paste-supplying means, and thereafter into contact with a magazine on said support; and means for imparting such oscillatory movement to 70 said member.

11. In a wrapping machine, the combination of wrapper-feeding means including a pair of feed rollers movable toward and away from each other; article-feeding 75 means; a rock-shaft; a member on said rock-shaft arranged to be engaged by an article to rock said shaft; and means operable by said rock-shaft to prevent said feeding rollers from moving toward each other to feed 80 a wrapper.

12. In a machine for wrapping magazines, the combination of wrapper-feeding means including a stationary roller and a pivoted arm carrying a roller arranged to 85 coöperate with said stationary roller; magazine feeding means; a rock-shaft; a member on said rock-shaft adapted to be engaged by the magazines; and a second member on said rock-shaft adapted to engage 90 said arm to prevent the movable feeding roller from being moved into operative engagement with said stationary roller.

13. In a machine for wrapping magazines, wrapper-folding means comprising 95 coacting rollers and a folding blade, a stop to position a magazine adjacent to said folding means, and means to move said stop toward said folding means to assist said blade in inserting the magazine between the 100 rollers.

14. In a machine for wrapping magazines, wrapper-folding means comprising two coacting rollers and a folding blade, a stop to position a magazine in a plane substantially parallel with a plane passing through the axes of the rollers, and means to move said stop toward the folding blade to assist said blade in inserting the magazine 105 between the rollers. 110

15. In a machine for wrapping magazines, the combination of a horizontal support for wrappers, means for placing wrappers thereon, means above said support for folding a magazine and for pushing the 115 folded magazine and a wrapper through said support, means beneath said support for completing the folding of the wrapper, means beneath the support for applying paste to the partially folded wrapper before the completion of its folding, and means for preventing the application of paste to a magazine which is presented without a surrounding wrapper. 120

16. A machine for wrapping magazines 125 having, in combination, a pair of coacting rollers disposed side by side, a third roller disposed parallel to and beneath one of the first mentioned rollers and coacting with the latter to perform the folding operation, a 130

folding blade arranged to push the article to be folded between said third roller and its coacting roller, and means for periodically moving said third roller away from its coacting roller when said blade is inserting an article therebetween whereby to facilitate the entrance of the article.

In testimony whereof I affix my signature in the presence of two witnesses.

CARL F. ANDERSON.
